UNITED STATES PATENT OFFICE

EDWARD M. PFAUSER, OF MILWAUKEE, WISCONSIN, ASSIGNOR TO THE BLACKHAWK MANUFACTURING COMPANY, OF MILWAUKEE, WISCONSIN

SOCKET WRENCH

Application filed July 30, 1930. Serial No. 471,710.

This invention relates to new and useful improvements in socket wrenches, and more particularly to a reversible socket wrench.

One of the objects of my invention is the provision of a reversible socket wrench which includes the reversible push plug structure, wherein the socket portion of the wrench can be applied to the plug upon either side of the ratchet head.

10 Another object of my invention is the provision of a novel structure of the above type wherein the push plug is so fitted to the ratchet head that should the plug become broken it can be quickly and easily replaced 15 with a new one.

In the construction of wrenches of this character, the reversible push plug is usually maintained in position by means of a pin carried by the ratchet head and operating in 20 a groove in the push plug for limiting the movement of the push plug with respect to the head and causing the same to rotate with the head.

One of the main objections which has been 25 found in the construction of this type of wrench, is the fact that heretofore the pin has been press-fitted through the hub of the ratchet end, therefore, when the push plug breaks off, it is necessary to drill out the pin 30 before a new one can be fitted in place.

A further object of my invention is the provision of a reversible socket wrench wherein the retaining pin which holds the push plug in place is fitted into the hub of 35 the ratchet in such manner that it can be quickly and easily removed for replacement or when the push plug is broken off, a new plug can be quickly fitted in place without the necessity of refitting the ratchet hub with 40 a new pin.

With the above and other objects in view, the invention consists in the novel features of construction, the combination and arrangement of parts hereinafter more fully set forth, pointed out in the claims and shown in the accompanying drawings wherein:

Figure 1 is a vertical sectional view 50 through my improved socket wrench;

Figure 2 is a sectional view at right angles to Figure 1, with parts in elevation; and Figure 3 is a detailed transverse section.

In the general construction of wrenches of this type, I have included a substantial hollow handle portion 1 which terminates at its upper end in a head 2 provided with opposed openings for receiving the bearing portions 3 of the ratchet head. The ratchet head is formed with a plurality of ratchet teeth 4 adapted to be engaged by a pivoted pawl 5, the movement of which in one direction is limited by means of a cross pin 6.

In the construction of wrenches of this type, the ratchet head is provided with a substantially rectangular opening 7 in which is slidably mounted a reversible push plug 8. This plug 8 is adapted to have one end thereof fitted and retained within the ratchet head 3, while the other end projects beyond 70 one side of the ratchet head and receives thereon the usual nut socket which is ordinarily used with wrenches of this type.

The plug 8 is provided with transverse bores 9 having reduced neck portions forming 75 annular shoulders 10 adjacent the outer ends of the bores. Arranged within the bores 9 are the stop lugs 11 having annular shoulders adapted to abut the shoulders 10 for limiting the outward movement of these lugs. The 80 inner ends of the lugs are each provided with a recess in which one end of the coil spring 12 is fitted, the other end of said spring bearing against the inner end of bore 7.

Normally, the outer end of each lug 11 85 projects beyond one face of the plug 8 and the lugs at the ends of the plug are adapted to be received within longitudinal grooves 13, extending inwardly from opposite ends of the ratchet head 3, and at the innermost end 90 of the grooves there are recesses or indentations 14 in which the rounded heads 15 of the lugs 11 are engaged to retain them in proper position, as shown in Figure 1.

Each groove 13 terminates at one side of 95 the transverse center of the ratchet head, thus leaving a stop shoulder disposed between the two grooves 13, forming a stop for the lugs 11 when the plug is pushed in either direction, so that the lugs 11 will have their 100

rounded ends properly seated within the indentations 14.

From the illustration in Figure 1, it will be noted that one end of the plug 8 is projected beyond one side of the head 3 to receive thereon the usual nut socket used in connection with wrenches of this type, and the plug will be securely held in this position by means of the lug at the right which is seated within its respective indentation 14 and bears against the dividing shoulder between the two grooves 13. When it is desired to shift the position of plug 8 from that shown in Figure 1, pressure exerted on the outer end of the plug will have a tendency to cause the outer end of plug 11 to be disengaged from the indentation 14 at the right, and this is easily accomplished due to the rounded head 15 of the lug. The block is then pushed endwise until the lug at the left hand end of the plug is engaged within the indentation of the left side of the ratchet head.

It will be apparent from this construction that should the push plug become broken off through application upon heavy work, the parts of the plug can be quickly and easily removed from the ratchet head.

In Figure 3, I have illustrated a slightly modified form of the invention wherein the bore 9' opens at both sides of the push plug 8' and one side of the plug has an opening which is slightly more restricted than the opening at the other side and engaged within this restricted opening is a ball 16, urged into the opening by means of the coil spring 12' which is positioned between the ball and the stop lug 11'.

In this form of the invention, the grooves 13' terminate upon opposite sides or the center of the ratchet head 3' to form a stop shoulder 14', against which lugs 11' abut when the push plug is moved longitudinally in either direction.

It will be noted that in this form of the invention the ratchet head is provided with spaced recesses 17, arranged upon opposite sides of the center of the ratchet head 3' and these recesses are adapted to receive the projecting portion of balls 16, as shown at Figure 3, to assist in retaining the push plug 8' in its operative position, as shown in Figure 3.

When it is desired to urge the push plug 8' from the position shown in Figure 3 to the other side of the ratchet head, it is only necessary to exert pressure to the outer end of the push plug which will have a tendency to release the ball 16 now engaged with its respective recess 17 and engage the other ball 16 with its respective recess, thus the push plug can be projected from either side of the ratchet head 3' and securely held in operative position. However, should the push plug become broken off through application upon heavy work, the broken parts of the plug

can be quickly and easily removed from the ratchet head.

In the manufacture of wrenches of this type, it has been found that in order to curtail expenses in the manufacture of these wrenches and produce a wrench whereby the push plugs can be easily replaced when broken, the structure described above and illustrated in the accompanying drawings is far superior to any known at the present time, and the effectiveness of the wrench is not interfered with in any manner whatever.

I claim:

1. A wrench of the class described including a ratchet head having an axial opening therethrough, a movable element positioned within the opening, said head having longitudinal grooves extending inwardly from opposite sides thereof at one side of the opening and yieldable members carried by the movable element and positionable within said grooves to provide stops to limit the movement of the movable member axially in either direction.

2. A wrench of the class described including a ratchet head having an axial opening, a push plug movably mounted in said opening, grooves in the ratchet head at one side of the opening extending inwardly to a point adjacent the center of the ratchet head, said ratchet head having recesses at one side of the opening and spring-pressed members carried by the push plug and adapted to engage within said grooves and recesses for retaining the push plug in projected position upon either side of the ratchet head.

3. A wrench of the class described including a ratchet head having an axial opening, a groove in the head extending inwardly from each side thereof to a point adjacent the center of said head, said head having recesses upon opposite sides of the center and at one side of the axial opening, a push plug longitudinally movable in the opening, spring-pressed lugs carried by the push plug and having their outer ends adapted to be disposed within said grooves, and spring-pressed ball members carried by the push plug and adapted to be engaged in said recesses for retaining the push plug in position with either end projecting from either side of the ratchet head.

In testimony that I claim the foregoing I have hereunto set my hand at Milwaukee, in the county of Milwaukee and State of Wisconsin.

EDWARD M. PFAUSER.
